UNITED STATES PATENT OFFICE.

DAVID E. BOWN, OF CRAFTON, PENNSYLVANIA.

ELECTRICAL PLUG.

1,184,313.

Specification of Letters Patent. Patented May 23, 1916.

Application filed July 12, 1915. Serial No. 39,503.

To all whom it may concern:

Be it known that I, DAVID E. BOWN, a citizen of the United States, residing at Crafton, in the county of Allegheny and State 5 of Pennsylvania, have invented a new and useful Improvement in Electrical Plugs, of which the following is a specification.

My invention relates to electrical plugs and more particularly to electrical plugs 10 wherein the plug body is surrounded with a metallic screw shell for insertion within the socket for engaging the necessary contact connected to the supply of electric current from the line.

15 The object of my invention is to provide a cheap, simple and efficient form of electrical plug, wherein the screw shell which is used for fostering, may be quickly and conveniently attached or detached from the 20 socket into or from which said plug is intended for use. Thus, my invention is designed for use, either as a connecting plug or as a fuse plug, as its principles are applicable to either.

25 A further object of my invention is to provide a plug, either attachment plug or fuse plug, wherein the screw shell surrounding the same may be quickly removed or attached to provide for connecting the terminal wires, or to provide for renewing the 30 fuse wire, provided the same has been blown out.

My invention consists, generally stated, in the novel arrangement, construction and 35 combination of parts as hereinafter more specifically set forth and described, and particularly pointed out in the claims hereunto appended.

40 To enable others skilled in the art to which my invention appertains to construct, use, and install any improved electrical plug, I will describe the same more fully, referring to the accompanying drawing, in which:

45 Figure 1 is a side view of any attachment plug, showing the screw shell and insulating sleeve in section, and my invention applied thereto. Fig. 2 is a side view of the attachment plug, shown in Fig. 1 looking in the direction of the arrow A, in Fig. 1, and 50 with the screw shell and insulating sleeve in section. Fig. 3 is a similar view looking in the direction of the arrow B in Fig. 1. Fig. 4 is a cross sectional view of the 55 same on the line 4-4 of Fig. 2 looking in the direction of the arrow C, in said figure and with the screw shell and the in-

sulating sleeve removed. Fig. 5 is a side view of a fuse plug with the screw shell and insulating shell shown in section, and showing any invention applied thereto, also having the top portion of the body invention in section to show the construction thereof. Fig. 6 is a perspective view of the insulating sleeve as used with the fuse plug shown in Fig. 5. Fig. 7 is a top plan view of the 65 spring ring employed to secure the screw shell, in position as shown in Figs. 1 to 5 inclusive.

Like symbols of reference herein, indicate 70 like parts in each of the figures of the drawing.

As illustrated in the drawing, the attachment plug shown in Figs. 1 to 4, consists of a body member 1, which has a head or top portion 2, attaching portion 3, and base 75 portion 4. This main member 1 is formed of any suitable material such as fiber, hard rubber or condensite and the attaching portion 3 extends diametrically from the periphery of the base portion 4 as shown in 80 Figs. 2 and 3. The top portion 2 is provided with a suitable recess 5 for receiving the wires 6 and 7 for connection, to the several terminals provided on said attaching portion 3, leading from the recess 5 are two 85 holes 8 and 9 through which the wires 6 and 7 are adapted to pass and said wires after passing through said holes are knotted as at 10 in order to relieve the binding posts 90 of any strain as later explained.

On the side face 11 of the body member 1 is a contact plate 12 which is secured in position by means of a screw 13 and said contact plate extends around the side of the base portion 4 and is provided with a small 95 semi-circular end 14 which fits into an annular groove 15 as later explained. The side face 16 of the body member 1 is also provided with a contact plate 17 which is secured in position by means of the screw 18 100 and said plate extends through a small opening 19 in the base 4 of said body portion and is turned at right angles in order to form the contact 20 for making the necessary connection in the usual socket. The 105 contact plates 12 and 17 are provided with binding posts 21 and 22 and to these posts are connected respectively the wires 6 and 7.

The plug shown in Figs. 1 to 4 is of the swivel type but I do not limit myself to this 110 construction as a non-swivel plug may embody my invention. The swivel type shown

in Fig. 1 is provided with the usual metallic screw shell 23 connected at its upper end to a fiber or other ring 24 while the lower end of said shell extends slightly above the upper end of the annular groove 15 and when said screw shell has been placed around said body member 1 a spring ring 25 is sprung into said annular groove and thus the said screw shell is prevented from becoming accidentally disengaged. This spring ring also engages with the contact plate 12 by passing over the semi-circular end 14 thereof and as the screw shell when screwed into a socket is always pressed tightly against the spring ring 25 a good electrical contact is always assured. Between the screw shell 23 and body member 1 is an insulating member 26, which is formed preferably of fiber or fullerboard and such ring is slightly recessed as at 27, in order to permit the contact plate 12 to pass therethrough to connect with the spring ring 25.

In Fig. 5 I have shown a fuse plug 29 embodying my invention, said plug having a body member 30 which is composed of glass or some other transparent material and such body member consists of the observing portion 31 having a heavy flange member 32 around the same and suitable notches 33 on the lower face of said flange for fitting into recesses 34 on the upper end of the screw shell 35 to prevent said shell from turning upon said body member. The attaching portion 36 of said body member 30 is provided on its attaching face 37 with a spring contact plate 38 which is secured to said face by the screw 39 and the outer spring end of said contact is adapted to extend through the slot 40 of the insulating sleeve 41 and engage the screw shell 35 at all times. The attaching face 42 of said portion 36 is provided with a contact plate 43 which is secured to said face by means of the screw 44 and extends through the opening 45 in the base portion 46 and is turned at right angles against the lower face of said base in order to form the contact 47. The contact plates 38 and 43 are provided with the binding posts 48 and 49 respectively and a fuse wire 50 extends through a hole 51 in the attaching portion 36 and connects by its ends with the said binding posts. The screw shell 35 is secured in position by means of the spring ring 52 which fits into the annular groove 53 as in the form of plug shown in Fig. 1.

It will readily be seen that with the use of the spring ring and groove the screw shell can be quickly and conveniently secured in position and no screws will be used for this purpose thereby saving considerable time and labor. The spring ring can be quickly removed from the groove when required by inserting any implement under one end of the same and raising it from

said groove. It will also be apparent that the chances for short circuits will be minimized by the construction of the body member as the central attaching portion prevents any electrical connection between the two circuits.

In the case of the fuse plug shown in Fig. 5 the burnt out fuse can readily be removed and renewed and the parts put together without any great loss of time.

It will readily be seen that when attachment plugs of the non-swivel type are used, the contact plate 12 of Fig. 1, may be omitted and the spring contact 38 shown in Fig. 5 may be used in its stead, thereby eliminating the semi-circular end of the contact plate 12, connecting with the spring ring 25.

Various modifications and changes in the design and construction of my improved plug may be resorted to, without departing from the spirit of the invention or sacrificing any of its advantages.

What I claim as my invention and desire to secure by Letters Patent is:—

1. A plug for electrical uses comprising a single integral main member, an annular groove therein, a removable screw shell fitting around said body portion; and means fitting into said groove and against said shell to prevent the removal thereof.

2. A plug for electrical uses comprising a single integral main member, an annular groove therein, a removable screw shell fitting around said body portion; and a spring ring fitting into said groove and against said shell to prevent the removal thereof.

3. A plug for electrical uses comprising a main member having an annular groove therein, a screw shell fitting around said main member, and means fitting into said groove and against said shell to prevent the removal thereof.

4. A plug for electrical uses comprising a main member having an annular groove therein, a screw shell fitting around said main member, and a spring ring fitting into said groove and against said shell to prevent the removal thereof.

5. A plug for electrical uses comprising a main member having a central attaching portion thereon, a contact on each side of said attaching portion; an annular groove extending around said body portion; a screw shell fitting around said main member, and means fitting into said groove and against said shell to prevent the removal thereof, one of said contacts having an electrical connection with said means.

6. A plug for electrical uses comprising a main member having a central attaching portion thereon, a contact on each side of said attaching portion; an annular groove extending around said body portion; a screw shell

fitting around said main member, and a spring ring fitting into said groove and against said shell to prevent the removal thereof, one of said contacts having an electrical connection with said spring ring.

7. A plug for electrical uses comprising a single main member having a central attaching portion with a recess on each side of the same, a contact plate on each recess, an annular groove extending around said body portion; means fitting into said groove and against said shell to prevent the removal thereof, one of said contact plates having an electrical connection with said means and the other contact plate passing through a slot in said body portion and providing a contact thereon.

8. A plug for electrical uses comprising a

single main member having a central attaching portion with a recess on each side of the same, a contact plate on each recess, an annular groove extending around said body portion; a screw shell fitting around said body portion; a spring ring fitting into said groove and against said shell to prevent the removal thereof, one of said contact plates having an electrical connection with said spring ring and the other contact plate passing through a slot in said body portion and providing a contact thereon.

In testimony whereof I affix my signature in the presence of two witnesses.

DAVID E. BOWN.
